OTTO C. BUSS, OF HAVRE, FRANCE, ASSIGNOR TO SOCIÉTÉ ANONYME POUR L'EXPLOITATION DES PROCÉDÉS WESTINGHOUSE-LEBLANC, OF PARIS, FRANCE.

ROTARY AIR-COMPRESSOR.

1,192,855.

Specification of Letters Patent.

Patented Aug. 1, 1916.

Application filed April 15, 1910. Serial No. 555,718.

To all whom it may concern:

Be it known that I, Otto C. Buss, a citizen of the Republic of Switzerland, residing at 2 Boulevard Sadi-Carnot, Havre, France, 5 have invented a new and useful Improvement in Rotary Air-Compressors, of which the following is a specification.

This invention relates to rotary air pumps of the well known Westinghouse-Leblanc 10 type in which the air or other fluid to be extracted is entrained by jets, streams or sheets of water or other liquid which are projected into the suction or vacuum chamber of the pump by means of a reversely 15 driven turbine. The liquid and entrained air or other fluid which may include also condensed vapors is forced through a nozzle, then through a combining tube or chamber into a second diverging nozzle from which 20 the extracted fluid and liquid are discharged.

I have found by experiment that the pressure in the combining tube or chamber above mentioned can and usually will be greater than the pressure in the suction or vacuum 25 chamber of the pump unless of course these two chambers are connected together by a conduit as is the case when the apparatus is employed as a steam condenser as shown in Figure 1.

According to my invention I connect the combining tube or chamber in the apparatus above mentioned to a chamber or space where it is desired to maintain a less vacuum than in the main suction or vacuum chamber of 35 the pump, by which means I am enabled with a single pump to extract air or other gases from two places where different pressures exist. By dividin, the combining tube or chamber into several parts a number of 40 different chambers may be exhausted to different pressures with the same pump if desired.

In order that the nature of the invention may be clearly understood the same will now 45 be described with reference to the accompanying drawings in which:—

Fig. 1 is a vertical sectional view of a Westinghouse Leblanc condenser or pump and Fig. 2 is a similar view showing the invention applied thereto: Fig. 3 is a diagrammatic view showing the invention as applied 50 to a sugar refining plant in which a plu-

rality of vacuum pans are employed: Fig. 4 is a view similar to Fig. 2, illustrating a modified construction.

Referring now to Fig. 1, the condenser 1 comprises a vacuum chamber 2 in which is mounted a reversely driven turbine wheel 3 which is supplied with liquid from a nozzle 4 arranged on the inside of the said wheel. 5 The turbine wheel 3 is driven by any suitable means and is provided with blades 5 by which the liquid is projected into the vacuum chamber in jets, streams, or sheets, and forced together with the entrained air 6 and condensed steam through a nozzle 6 located in the lower portion of the vacuum chamber 2. The nozzle 6 communicates with a combining tube or chamber 7 which is in open communication with the atmosphere or 70 hot well by means of a converging-diverging nozzle 8. The chamber 7 is connected with the vacuum chamber 2 of the condenser by means of a passage 25 formed in the wall of the condenser casing.

I have found that if the passage 25 leading from the vacuum chamber 2 to the chamber 7 is omitted, the pressure in the chamber 7 will be increased and will consequently become greater than the pressure existing in 80 the vacuum chamber 2. According to my invention, as shown in Fig. 2, the chamber 7 is connected by a pipe 9 to a point where a pressure greater than the pressure in the chamber 7 exists, by which means air and 85 incondensable gases are extracted from this point without in any way altering the degree of vacuum maintained in the vacuum chamber 2 and without increasing in any way the power required by the apparatus. 90 As an example, with an air pump of this description capable of producing a vacuum of 736 mm. of mercury at a barometric pressure of 748 mm., I have found that a series of converging nozzles of various diameters 95 may be employed for connecting the chamber 7 to the atmosphere and the vacuum in the vacuum chamber 2 still maintained equal to a pressure of 736 mm. of mercury. Experiments have been made with nozzles of 100 various dimensions, the diameters at the neck of the various nozzles employed being as follows: 2 mm., 4 mm., 6 mm., 8 mm., 10 mm., 12 mm., 14 mm., 16 mm. The vacuum

in the vacuum chamber 2 being equal to 736 mm. the following degrees of vacuum were obtained in chamber 7:—

Without a nozzle	710	mm.
With nozzle of 2 mm. diameter	680	"
" 4	640	"
" 6	605	"
" 8	570	"
" 10	537	"
" 12	465	"
" 14	355	"
" 16	260	"

Therefore with a single pump it is possible to extract the incondensable gases from two points where different pressures exist.

In Fig. 3 I have indicated how my invention may be applied to a series of vacuum pans in sugar refining apparatus, such a series of pans being commonly known as a "multiple effect." In this figure the main suction 10 of the air pump 11 is connected to an injection or surface condenser 12 which in turn is connected to the last pan 13, of a series of similar pans 14, 15, 16, 17, 18, forming a sextuple effect in which pan 13 the maximum degree of vacuum exists (98% of the barometric pressure for example.) The converging nozzle 19 of the pump which is located in the chamber 7 and is connected by pipe 9 to the second pan 14 of the series where a vacuum in the neighborhood of 60% of the barometric pressure is maintained. It will be seen that the incondensable gases coming from the vacuum chambers of the reservoirs 18, 17, 16, 15, or from the air inlets in the system in which the vacuum is to be obtained, up to this chamber being previously exhausted, the vacuum in the condenser will be greatly improved. Actual experiments made on a system of this description, the barometric pressure being 748 mm., showed that the vacuum obtained in the vacuum chamber of the condenser, the passage 25 being omitted as before explained so that the chamber 7 was closed, did not exceed 660 mm. of mercury; on the other hand, the chamber 7 being connected to the outlet of the second pan as shown in Fig. 3, the vacuum in the condenser and in the suction 10 of the air pump corresponded to a pressure of 698 mm. of mercury, while the vacuum in the chamber 7 and the outlet of the second pan corresponded to a pressure of 500 mm. of mercury, the working conditions remaining strictly the same. A similar arrangement may be employed in connection with injection condensers in which the air is extracted from the injection water prior to its entrance into the condenser. It is sufficient for this purpose to connect the chamber 7 of the air pump to an air separating chamber located between the con-

denser and the source of supply of condensing water, and adapted to free the air dissolved in the water prior to its entrance into the condenser, the outlet for the air from the condenser being connected to the chamber 2.

Instead of connecting the chamber 7 to a single reservoir, a plurality of reservoirs may be exhausted to a different degree of vacuum, in which case a series of nozzles 19, 20, 21 are provided having inlets 22, 23, 24 formed in the wall of the chamber 7 adjacent to and on the underside of each nozzle connected respectively to the several reservoirs; such an arrangement is possible with the device which is shown in Fig. 4.

It will be understood that the invention is not limited to the particular constructions herein described and illustrated, as various modifications may be made therein without exceeding the scope of the invention.

I claim as my invention:—

1. In combination with a chamber provided with an inlet for fluid and an outlet, rotary means arranged so as to project liquid into said chamber between the inlet and outlet thereof and one or more fluid inlets between the entrance point of said liquid and said fluid outlet.

2. An apparatus of the character described, comprising an admission chamber, having a fluid admission port and a discharge port, a combining chamber communicating with the discharge port and provided with at least one auxiliary fluid admission port, a divergent discharge nozzle communicating with said combining chamber and means for projecting an interrupted stream of liquid at a high velocity into said admission chamber and through said combining chamber and said discharge nozzle, said means comprising a partial ejection rotatable impeller.

3. An apparatus of the character described, comprising an admission chamber having a fluid inlet, a discharge nozzle communicating with said chamber, a combining chamber communicating with said nozzle and provided with separate admission ports, convergent tubes extending across and dividing said combining chamber into separate sections each of which communicates with one of said ports, and a liquid impeller located between the inlet of said admission chamber and said nozzle for discharging liquid through said nozzle, said combining tube, and said diffuser.

In testimony whereof I have hereunto subscribed my name this fourth day of April, 1910.

OTTO C. BUSS.
